MEANS FOR MEASURING YARN IN PIRN
AND LIKE WINDING APPARATUSGeorge Arthur Armett, Arthur Prince Black, and
Stephen Miller Fulton, Spondon, near Derby,
England, assignors to Celanese Corporation of
America, a corporation of DelawareApplication October 23, 1934, Serial No. 749,568
In Great Britain November 7, 1933

10 Claims. (Cl. 33—136)

This invention relates to means for measuring yarn in pirn-winding and like winding apparatus, and is particularly concerned with means for enabling a predetermined length of yarn to be wound on to the pirn tube or other support.

In many textile winding operations, e. g. in the production of weft pirns for weaving, it is of great importance with a view to enabling them to be used to advantage on a loom fitted with a weft-measuring stop-motion to be able to ensure that each pirn shall contain, within small limits, the same amount of yarn. Attempts have been made to provide apparatus whereby the amount of yarn wound on to a pirn can be predetermined, for example by causing the yarn to pass round a roller or like device on its way to the pirn tube, means being provided whereby the spindle of the winding machine is brought to rest when the roller has made a certain number of revolutions. Such apparatus, however, is subject to certain disadvantages. Thus, for example, the reliability of the device is diminished by the great possibility of slip between the yarn and the roller, while the device, having to be driven by the yarn itself, may cause stretching of the yarn, which is a frequent cause of uneven dyeing and is particularly objectionable since it may not be detected until the fabric has been made or even dyed. These disadvantages are particularly evident when the yarn is of smooth character, for example when it consists of continuous artificial filaments since it is then more likely to slip. It is well known, moreover, that in the processing of continuous filament yarns, it is particularly important to avoid strains.

The present invention is concerned with apparatus the object of which is to enable the amount of yarn wound into a pirn or other package to be predetermined to a relatively high degree of accuracy while avoiding disadvantages inherent in methods such as that referred to above. The apparatus can readily be manufactured in a compact form, capable of application to existing types of pirn winding and like machines, and is inexpensive and simple in operation. Moreover, it may be made entirely automatic so that its accuracy does not depend upon any adjustment by the operative. It is capable of application in connection with supply packages of any desired form.

The apparatus of the invention comprises a member adapted to be driven at a predetermined rate from the spindle drive of the machine, and means actuated by said member for stopping the rotation of the spindle when the predetermined amount of yarn has been wound on to the package carrier. The spindle drive may, for example, drive through suitable reduction gear a notched disc or the like, by the rotation of which the stop mechanism is actuated. In the preferred

form of the invention, the stop mechanism is actuated by a weighted or spring-loaded lever, which bears upon the periphery of a slotted disc driven through worm gearing from the spindle drive. The stop mechanism, which is ordinarily out of operation, is caused to operate by the fall of the lever into the slot of the disc. A simple form of stop device comprises a member adapted to be moved behind an abutment on the traverse mechanism so as to release the starting and stopping lever and so make use of the ordinary stop-mechanism provided on such winding machines.

Conveniently the disc makes one full rotation before stopping the spindle, the rate of rotation of the disc being adjusted in accordance with the number of turns of the spindle necessary to fill the pirn tube. Such number of turns depends on the length and diameter of the tube and the denier or counts of the yarn. Means may be provided for altering the gear ratio between the spindle drive and the disc in accordance with any of these factors. Such means may very conveniently take the form of provision for replacing one or more of the gears between the spindle and the disc by gears of different size, sets of change wheels being provided for this purpose. The disc may be driven from any suitable part of the winding mechanism, e. g. from the spindle itself.

Preferably the apparatus is such that on restarting the machine after a stoppage, the stop actuating mechanism is automatically set for effecting the next stoppage of the spindle. Thus means may be provided for lifting, or assisting to lift, the weighted lever out of the slot in the disc, thus avoiding the necessity of supporting it above the slot during the relatively long time taken for the disc to revolve, so as to carry the slot out of the position of engagement with the stop lever. The slot in the disc may, for example, have a steep side, which allows the stop lever to drop into the slot, the sudden drop actuating the stop mechanism, and a sloping side up which the lever climbs on the continued rotation of the disc after restarting until it rides on the periphery thereof.

Various forms of apparatus according to the invention will now be described with reference to the accompanying drawings in which

Figs. 1 and 2 are part sectional front and side elevations of the measuring device showing the driving connection to the pirn-winding spindle;

Fig. 3 is a perspective view of the device mounted on one head of a pirn-winding machine;

Fig. 4 is another perspective view showing how the device operates to effect stoppage of pirn-winding; and

Fig. 5 is a diagrammatic view of a modified form of the device.

Referring to Figs. 1 and 2, the principal part 60

of the measuring device according to the invention is shown as comprising a gear box 10 adapted to be mounted on the gear box 11 of a pirl-winding head so as to lie above but somewhat to one side of the pirl tube spindle 12 projecting from the front of the box 11.

A worm 13 on the spindle 12 engages a worm wheel 14 on a spindle 15 carried by the box 10 and projecting through a hole 16 in one side of the box. Inside the box the spindle 15 is carried by a cradle 17 pivoted on a shaft 18, a worm 19 secured to the spindle 15 between the arms of the cradle 17 meshing with a worm wheel 20 on the shaft 18. A worm 21 and a worm wheel 22 connect the shaft 18 with a further shaft 23 extending outside the gear box 10 and carrying there a pinion 24. The pinion 24 meshes with a pinion 25 on a shaft 26 passing inside the box 10 and carrying a disc 27 that projects through a slot 28 at the top of the box. A slot 29 is formed in the periphery of the disc 27, one edge 30 of the slot being substantially radial, while the other edge 31 is inclined.

Pivoted on a bracket 32 carried by the box 10 is a lever 33 provided with a weight 34 at one end that causes it to rest on the periphery of the disc 27. To the other end of the lever 33 is secured a downwardly depending stiff wire 35.

By reason of the gear connection between the pirl tube spindle 12 and the disc 27, the disc is caused to rotate slowly, the ratios of the various gears being chosen so that the disc makes one revolution in the time required to complete the winding of one pirl, i. e. after a predetermined number of revolutions of the spindle 12. During winding, the weight 34 is held raised by the engagement of the lever 33 with the periphery of the disc 27. After one revolution of the disc the lever 33 is caused by the weight 34 to fall over the sharp edge 30 of the notch 29, so rocking the downwardly depending portion of the wire 35 to the left. This brings the wire to the dotted position shown in Fig. 3 behind the abutment 36 near the gear box end of the traverse rod 37. On the next rearward motion of the traverse rod, the abutment 36 drives the wire 35 against a member 38 projecting from an arm 39, and so rocks the arm about its pivot 40. This withdraws a latch 41 on the arm 39 from engagement with an arm 42 carried by the starting and stopping lever rod 43. The starting lever is thus allowed to rock and stop by spring action in the usual way the mechanism inside the gear box 11 by which the spindle 12 is driven.

Upon replacement of the wound pirl by an empty tube and re-setting of the starting lever 43, the disc 27 recommences its rotation, the lever 33 riding up the inclined edge 31 of the notch 29 until the lever again rests on the periphery of the disc. During the lifting of the lever 33 the mechanism is prevented from releasing the starting lever by means of a stiff wire 44 carried by the traverse mechanism 45, the wire 44 passing between the wire 35 and the abutment 36 until sufficient time has elapsed for the lever 33 to be lifted. The striking of the wire 35 by the wire 44 assists the lever 33 to ride up the incline 31. As traversing continues the wire 44 is drawn forwardly beyond the wire 35, so permitting the latter again to pass behind the abutment 36 when the pirl is completed.

In order that the device may be used for the winding of different amounts of yarn depending upon the size of the pirl and the denier or count of the yarn, different gear ratios may be employed

at the gears 13, 14 and 24, 25. In order to provide for the different ratio of the gears 13, 14, the spindle 15 is carried by a block 46 adjustably mounted in a curved slot 47 in a projection 48 of the gear box 10. The spindle 15 may thus be 5 swung about the shaft 18 to allow the gear 14 to be replaced by other gears of different sizes, the positions of the different gears 14 along the projecting end 15 being adjusted to bring the gears properly into mesh with the worm 13.

Each head of the pirl-winding machine is fitted with one of the devices above described, the gear ratios employed being adjustable for each individual case, if desired.

Referring to Fig. 5, a modification of the device 15 is shown employing a single gear box to control winding at a number of heads in one machine in the case where all the heads are required to wind the same amount of yarn on to each pirl. The modified device comprises a gear box 49 provided with a gear 50 driven from any suitable part of the machine, a reduction gear inside the gear box driving a shaft 51 through one revolution of the time taken to wind a pirl. Opposite each winding head a slotted disc 52 is disposed on the shaft 51, the disc being loosely mounted between a collar 53 secured to the shaft and a slotted member 54 behind which is disposed a strong spring 55 abutting against a further collar 56 secured to the shaft. During winding of the 30 pirl the spring 55 is allowed to press the member 54 firmly against the boss of the disc 52, so causing the disc to be driven at the speed of the shaft 51 by the frictional engagement between the disc and the collar 53.

A lever 57 pivoted at 58 is provided with a weight 59 at one end and at the other end is secured thereto a depending wire 60. The functions of the slotted disc 52, weighted lever 57 and wire 60 are the same as those of the disc 27, lever 33 and wire 35 of Figs. 1-4, the lever 33 falling into a notch 61 in the disc 52 to bring the wire 60 behind the abutment on the traverse rod.

The release of the starting and stopping lever rod 43 of the pirl winding head is effected as described with reference to Fig. 4, the rod rotating clockwise by means of the usual spring inside the winding head to stop rotation of the winding spindle. At the same time a lever 62 secured to the starting lever rod is rocked in a clockwise direction by the release of the rod 43 and through a link 63 rocks a lever 64 mounted on the same pivot 58 as the lever 57. A downwardly depending member 65 of the lever 64 engages the slot round the member 54 so that rocking of the lever 64 due to the release of the starting lever rod withdraws the member 54 from engagement with the slotted disc 52, overcoming the spring 55 and allowing the disc 52 to remain stationary notwithstanding continuance of the drive of the shaft 51.

In order to ensure that the disc 52 does not commence rotation until the starting lever rod 43 has been operated to recommence winding on an empty pirl tube, the lever 64 is provided with a projecting member 66 extending towards the disc 52. When the lever 64 is rocked to release the disc 52, the projecting member 66 is rocked into the path of a small block 67 secured to the face of the disc. So long as the starting lever rod remains released, the projecting member 66 engages the block 67 and prevents rotation of the disc 52. When the starting lever rod is operated to recommence winding, the projecting member 66 is removed from engagement with the block 67 at the same time as the member 65 allows the 75

spring 55 to urge the member 54 against the boss of the disc 52 to bring about the frictional drive of the disc from the shaft 51.

Though in this modification all the heads controlled by the gear box 49 must complete their winding at the same time, winding at each head takes place independently of the others, since timing of the frictional drive of the particular slotted disc 52 is controlled only by the operation 10 of the starting lever rod 43 of the corresponding winding head.

What we claim and desire to secure by Letters Patent is:—

1. In a pirn winding or like machine comprising 15 a winding spindle provided with stop mechanism and a yarn traversing mechanism, a yarn measuring device including a member adapted to be driven at a predetermined rate relative to the winding spindle, and means controlled by said 20 member to be engaged by the traversing mechanism after a predetermined number of revolutions of the winding spindle, to operate the stop mechanism for the winding spindle.

2. In a pirn winding or like machine comprising 25 a winding spindle provided with stop mechanism and a yarn traversing mechanism, a yarn measuring device including a notched disc in geared driving connection with the winding spindle, a lever adapted to be supported by the edge 30 of said notched disc, and means controlled by said lever to be engaged by the traversing mechanism after a predetermined number of revolutions of the winding spindle to operate the stop mechanism for the winding spindle.

3. In a pirn winding or like machine comprising 35 a winding spindle provided with stop mechanism and a yarn traversing mechanism, a yarn measuring device including a notched disc in geared driving connection with the winding spindle, said geared driving connection containing 40 exchangeable gears, a lever adapted to be supported by the edge of said notched disc, and means controlled by said lever to be engaged by the traversing mechanism after a predetermined 45 number of revolutions of the winding spindle to operate the stop mechanism for the winding spindle.

4. Yarn measuring device for application to 50 pirn winding and like machines comprising a winding spindle having stop mechanism, said device comprising a rotatable member, gearing adapted to be put in driving connection with a winding spindle of a machine so as to effect rotation of said member and a member controlled by 55 said rotatable member to engage with the traversing mechanism after a predetermined number of revolutions of the spindle to actuate the stop mechanism for the spindle.

5. Yarn measuring device for application to 60 pirn winding and like machines comprising a winding spindle having stop mechanism, said device comprising a notched disc, gearing adapted to be put in driving connection with a winding spindle of the machine so as to effect rotation 65 of said disc, a lever adapted to rest on the edge of said disc, and a member connected to said lever and adapted to engage with the traversing mechanism of the machine to actuate the stop mechanism for the spindle when the rotation of said disc brings the notch beneath the lever.

6. Pirn-winding and like machines, comprising 70 a yarn-measuring device including a notched disc in gear driving connection with the winding spindle of the machine, said gear driving connection 75 comprising a worm on the winding spindle, a

worm-wheel spindle and a pivotal mounting for the worm-wheel spindle, said spindle being adjustably positioned to allow exchangeable worm-wheels to be carried by the spindle and brought into mesh with the worm on the winding spindle, 5 a lever adapted to be supported by the edge of the disc and means actuated by the lever adapted to effect stopping of the spindle, said means being actuated when the rotation of the disc brings the notch beneath the lever. 10

7. Pirn-winding and like machines, comprising 15 a winding spindle, yarn traversing mechanism, starting and stopping means for said spindle, a member in geared driving connection with the winding spindle, and means actuated by said member comprising an abutment on the traversing means, a latch engaging the starting and stopping means and a member adapted to be moved into position and to be engaged by the abutment and caused thereby to release the latch, 20 said means being actuated by said member after a predetermined number of revolutions of the spindle to release the starting and stopping means, so stopping the rotation of the spindle. 25

8. In a pirn-winding or like machine comprising 30 a winding spindle and a yarn traversing mechanism, a yarn-measuring device including a notched disc in geared driving connection with the winding spindle, said geared driving connection comprising a worm on the winding spindle, a 35 worm-wheel spindle, a pivotal mounting for the worm-wheel spindle, said worm-wheel spindle being adjustably positioned to allow interchangeable worm-wheels to be carried by said worm wheel spindle and brought into mesh with the worm on the winding spindle, a lever adapted to be supported by the edge of said notched disc, and means actuated by said lever after a predetermined 40 number of revolutions of the winding spindle to cooperate with the traversing mechanism to stop the rotation of the winding spindle. 45

9. A pirn-winding or like machine comprising 50 a plurality of winding spindles and corresponding traversing mechanisms, a shaft, friction-driven notched discs mounted on the shaft adjacent each spindle, said discs being adapted to be driven at a predetermined rate relative to said spindle, 55 levers adapted to be supported by the edges of the discs, means connected to each lever to cooperate with the corresponding traversing mechanism to effect stopping of the corresponding spindle, said means being actuated when the rotation of the particular disc brings the notch beneath that lever, and means to disconnect the friction-drive between a disc and the shaft when the spindle corresponding to that disc is stopped. 60

10. A pirn-winding or like machine comprising 65 a plurality of winding spindles and corresponding traversing mechanisms, a shaft, friction-driven notched discs mounted on the shaft adjacent each spindle, said discs being adapted to be driven at a predetermined rate relative to said spindle, levers adapted to be supported by the edges of the discs, means connected to each lever to cooperate with the corresponding traversing mechanism to effect stopping of the corresponding spindle, said means being actuated when the rotation of the particular disc brings the notch beneath that lever, and means to prevent rotation 70 of a disc when the spindle corresponding to that disc is stopped. 75
